WELL FLOWING APPARATUS

Lynn M. Trawick, Stroud, Okla.

Application September 3, 1940, Serial No. 355,273

5 Claims. (Cl. 103—233)

This invention relates to improvements in the pneumatic lifting of fluids from wells, and more particularly but not by way of limitation, to the arrangement of an intermittent flow apparatus in a well hole. This application relates to subject matter disclosed but not claimed in applicant's copending application, Serial No. 355,274, filed September 3, 1940.

An important object of this invention is to provide an inlet collar to the eduction tubing employed in the flowing of oil from the well hole, said collar being constructed to control the directional flow of motive fluid pressure.

A further object of this invention is to provide a collar for the eduction tubing employed in the flowing of liquid from a well of such construction as to receive a plurality of control units determining the flow of fluid into the eduction tubing.

And still an additional object of this invention is to provide an intermittent system for flowing wells so arranged in the well that motive gas is directed into the tubing at a point depending upon the fluid level in the eduction tubing.

And still another object of this invention is to provide a collar for an eduction tubing employed in the flowing of oil from well holes so constructed and arranged with a plurality of passageways, part of which are to receive control devices for determining the flow of input gas through the collar and directing the gas against the liquid to be lifted at a point depending upon the liquid level.

And still a further object of this invention is to provide an automatic intermittent apparatus arranged in the eduction tubing employed in the flowing of liquid from a well in such a manner that the apparatus acts as a choke for decreasing the volume of liquid to be lifted thereby conserving the amount of motive fluid necessary to lift the liquid.

Other objects and advantages of the invention will be evident from the following detailed description read in conjunction with the accompanying drawing which illustrates one form of my invention.

In the drawing:

Fig. 1 is a fragmentary sectional elevational view with certain parts in elevation showing the arrangement of the device disposed in the well hole.

Fig. 2 is an enlarged sectional vertical view of the collar with certain elements attached thereto in elevation.

Fig. 3 is a view similar to Fig. 1 in part show-

ing a modified arrangement by the use of packing in the well.

Referring to the drawing in detail, the intermitting unit or system is arranged in a string of casing 2 shown disposed in a well, with the lower end of the casing in proximity of the shot hole 4. The upper end of the casing extends to the surface and is secured to any suitable casing head or the like (not shown). A string of tubing 6 extends from the surface of the well in spaced relation to the casing 2.

A collar 8 is interposed in the tubing 6 and is preferably threadedly secured between the tubing sections at a point fifty to a hundred feet above the normal liquid level of the well. The collar 8, clearly shown in detail in Fig. 2, is provided with a centrally disposed spider 10 having a vertical threaded bore or passageway 12. The passageway 12 intersects with a transverse passageway 14 providing communication therebetween. Sleeves or bushings 16 are threadedly secured at opposite ends of the bore 14.

As clearly shown in Figs. 1 and 2, the upper portion of bore 12 is adapted to receive a cylindrical housing 18 containing an intermitting valve unit controlling the flow of input air or gas into the bores 14 and 12 to be discharged into the eduction tubing 6. The details of the valve unit form no part of this invention, and will not be described here.

A string of smaller sized tubing 20 is secured in the lower portion of the passageway 12, and extends vertically downward from the collar 8 in spaced relation to the eduction tubing 6 extending downwardly from the collar 8. The smaller tubing 20 is interconnected by a plurality of couplings or valve collars 24 (Fig. 1) having associated therewith a differential valve unit (not shown in detail). The lower end of the tubing 20 is provided with a suitable "bull plug" or the like. The lower end of tubing 6 is provided with a plug 28. A plurality of perforations 30 are provided in the tubing in order to allow the free flow of oil from the shot hole into the interior 32 of the eduction tubing below collar 8.

The arrangement shown in Fig. 1 is for the use of pressure gas from the well itself, it being understood that the casing is blocked off at the surface of the well (not shown). In Fig. 3 a modified arrangement is shown by the use of packing 33 blocking off pressure gas from the well when it is desired to use surface gas from any suitable source (not shown).

Operation

In operation, motive fluid for lifting the liquid is maintained substantially constant in the space 36 provided between the eduction tubing and casing 2, and discharged into the sleeve 16, and bore 14, onto either the intermitting unit 18 or the smaller string of tubing 20 and lower valves (not shown) in collars 24 standing in the eduction tubing.

The lower valve units provided in collars 24 function to allow passage of motive fluid therethrough for lifting the liquid to a point above the collar 8 where the hydrostatic head of the well liquid will operate the intermitting valve unit 18 to allow passage of motive fluid therethrough for slugging the oil vertically upward in space 34 onto the surface. It will be apparent that the arrangement of the smaller tubing 20 and the valve collars 24 in the space 32 acts as a choke to decrease the volume in space 32, which in turn decreases the amount of volume of liquid to be lifted from this space to an elevation above the collar 8. Furthermore, it will be apparent that with less liquid to be lifted it will take a decreased amount of gas at a constant pressure thereby providing an economical and conservative use of motive fluid.

From the foregoing, it will be apparent that the construction and arrangement of the intermitting apparatus in the eduction tubing of the well is simple and efficient in that the smaller sized tubing of the cooperating valve collars acts as a choke for decreasing the volume of space for oil to be lifted, which decreases the frictional resistance of fluid flow, as well as conserves the volume of motive fluid in cubic feet for lifting the smaller volume of liquid above the collar where it is then aerated to the surface of the well.

Changes may be made in the combination and arrangement of parts as heretofore set forth in the specification and shown in the drawing, it being understood that any modification in the precise embodiment of the invention may be made within the scope of the following claims without departing from the spirit of the invention.

What I claim is:

1. In combination with a well tubing, a collar in said tubing, said collar having a spider disposed therein, an unobstructed transverse passageway therethrough, a second passageway provided in the spider in substantial alignment with the tubing and communicating with the first mentioned passageway, a string of small tubing secured in the lower portion of the second mentioned passageway and extending vertically downward from the collar in spaced relation to the well tubing, a plurality of collars interposed at successive elevations in the string of small tubing, said smaller tubing and collars adapted to act as a choke for decreasing the volume of space in the well tubing below the first mentioned collar.

2. In combination with a well tubing, a fitting comprising a spider disposed therein, an unobstructed transverse passageway therethrough, a vertical passageway provided in the spider and communicating with the transverse passageway, a string of small tubing secured in the vertical passageway and extending vertically downward from the fitting in spaced relation to the well tubing, a plurality of collars interposed at successive elevations in the string of smaller tubing and adapted to form a choke for decreasing the volume of space in the well tubing below the fitting, and a valve mechanism secured in the upper portion of the vertical passageway.
- 5 3. In a well flowing apparatus including an eduction tubing for conducting liquid from the well, an inlet collar for admitting motive fluid interposed in the tubing, an unobstructed transverse passageway provided in the collar, a vertical passageway provided in the collar and communicating with the transverse passageway, a string of small tubing secured in the vertical passageway and extending vertically downward from the collar in spaced relation to the well tubing, a plurality of valve collars having valves disposed therein interposed at successive elevations in the string of smaller tubing and cooperating with the small tubing to form a choke for decreasing the volume of space in the eduction tubing below the inlet collar.
- 10 4. In a well flowing apparatus including an eduction tubing for conducting liquid from the well, an inlet collar for admitting motive fluid interposed in the tubing, an unobstructed transverse passageway provided in the collar, a vertical passageway in the collar and communicating with the transverse passageway, a string of small tubing secured in the vertical passageway and extending vertically downward from the collar in spaced relation to the well tubing, a plurality of collars interposed at successive elevations in the string of smaller tubing cooperating with the small tubing to form a choke for decreasing the volume of space in the eduction tubing below the inlet collar, and an aerating valve secured in the upper portion of the vertical passageway.
- 15 5. In combination with the eduction tubing of an oil well, a motive fluid inlet collar interposed in the tubing, a transverse passageway provided in the collar, a vertical passageway provided in the collar and communicating with the transverse passageway, a string of smaller tubing secured in the lower portion of the vertical passageway and extending vertically downward from the collar in spaced relation to the eduction tubing, a plurality of valve collars having valves disposed therein and interposed at successive elevations in the string of small tubing and adapted to act as a choke for decreasing the volume of space in the well tubing below the collar.
- 20 6. LYNN M. TRAWICK.
